UNITED STATES PATENT OFFICE.

HOWARD H. FORREST, OF KENT, OHIO, ASSIGNOR TO THE ERIE TIRE & RUBBER COMPANY, OF CLEVELAND, OHIO, A CORPORATION OF OHIO.

DESIGN FOR A TIRE.

53,899.

Specification for Design.

Patented Oct. 7, 1919.

Application filed May 19, 1919. Serial No. 298,330. Term of patent 14 years.

To all whom it may concern:

Be it known that I, HOWARD H. FORREST, a citizen of the United States, residing at Kent, in the county of Portage, State of Ohio, have invented a new, original, and ornamental Design for Tires, of which the following is a specification, reference being had to the accompanying drawing, forming part thereof.

In the accompanying drawing:

Figure 1 represents a plan view of a section of a tire illustrating my new design;

Copies of this patent may be obtained for five cents each, by addressing the "Commissioner of Patents, Washington, D. C."

Fig. 2 represents a side elevation of the tire section shown in Fig. 1; and

Figs. 3 and 4 represent, respectively, vertical sections taken in the planes indicated by the lines III—III and IV—IV, Fig. 1.

I claim:

The ornamental design for a tire, substantially as shown.

Signed by me, this 12th day of May, 1919.

H. H. FORREST.
